UNITED STATES PATENT OFFICE.

ROSARIO DI RENZO, OF PORTLAND, MAINE.

SWIMMING DEVICE.

Application filed September 12, 1924. Serial No. 737,409.

To all whom it may concern:

Be it known that I, ROSARIO DI RENZO, a subject of the King of Italy, residing at Portland, in the county of Cumberland and State of Maine, have invented new and useful Improvements in Swimming Devices, of which the following is a specification.

This invention relates to swimming devices, and contemplates a device designed to be readily and easily attached to the foot and leg of the user, and including a pair of hingedly mounted wings adapted to fold at the sides of the leg when the foot is moved inwardly and to unfold and extend laterally from the leg when the foot is moved outwardly, thus providing a large area of surface which retards the outward movement of the foot, and thus materially assists or aids the user in pushing himself forwardly in the water.

In carrying out the invention I comprehend a device of the above mentioned character which is simple in construction so that it can be manufactured and sold at a nominal cost, with the wings so arranged that when the device is attached to the foot and leg, said wings will normally occupy an out of the way position so as not to interfere with walking.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a view showing how the attachment is arranged on the foot and leg of the user.

Figure 2 is a view showing the device removed and taken at a right angle to Figure 1, the normal position of the wings being shown in full lines, and their active positions illustrated by dotted lines.

Figure 3 is a view taken at a right angle to Figure 2 showing one of the wings in its active position.

Figure 4 is an enlarged sectional view through the device.

The device forming the subject matter of the present invention includes a substantially U-shaped member which is adapted to

be arranged beneath the instep of the user, with its parallel portions 10 arranged at the opposite sides of the leg. This member is held attached to the leg by means of straps 11 which are adapted to encircle the leg, each strap being provided with a buckle 12 as shown. The U-shape member may be constructed from metal, leather or any suitable material, and vary in size without departing from the spirit of the invention. Carried by each parallel portion 10 of the U-shape member is a wing 13, and when the device is placed upon the foot and leg of the user, these wings occupy positions at opposite sides of the leg, and sufficiently above the ground so as not to interfere with walking. Each wing 13 is attached to the adjacent parallel portion 10 of the U-shape member by a hinge 14 thus permitting the said wings to normally occupy the positions shown by full lines in Figure 2, in which positions the wings are arranged parallel with the portions 10 of the U-shape member, or allow the wings to move to their active positions shown by dotted lines in Figure 2. A chain 15 is terminally connected with each wing 13 and the U-shape member to limit the movement of said wing to its active position as will be readily understood.

Manifestly, when the device is arranged upon the foot and leg of the user as shown in Figure 1, and the leg is drawn inwardly during the act of swimming the wings move toward each other to their normal positions, so as not to offer any resistance to the movement of the leg in the direction mentioned. However when the foot and leg are moved outwardly, the wings 13 move away from each other to their active positions, shown by dotted lines in Figure 2, thus providing with the bottom of the foot a large area which offers considerable resistance to the outward movement of the foot and leg, which of course assists the user in pushing himself forwardly in the water.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:

In a swimming device, a substantially U-shaped narrow member adapted to be passed

beneath the instep of the foot of the user, means for attaching the parallel portions of said member to the ankle, relatively wide wings mounted on the parallel portions and projecting an appreciable distance beyond both sides thereof, a hinge connecting each wing with the adjacent parallel portion, each hinge including spaced side plates secured to the adjacent edges of the U-shaped

member and projecting beyond the opposed sides thereof to provide an effective support for the adjacent wing throughout its entire width, and a flexible element terminally connected with each wing and the U-shaped member to limit the outward movement of the wing.

In testimony whereof I affix my signature.

ROSARIO DI RENZO.
